UNITED STATES PATENT OFFICE.

EDWARD P. POOLE, OF CONNELLSVILLE, PENNSYLVANIA.

TAPPING-VALVE.

1,112,093.

Specification of Letters Patent. Patented Sept. 29, 1914.

Application filed January 15, 1913. Serial No. 742,269.

To all whom it may concern:

Be it known that I, EDWARD P. POOLE, a citizen of the United States, residing at Connellsburg, in the county of Fayette and State of Pennsylvania, have invented new and useful Improvements in Tapping-Valves, of which the following is a specification.

The invention relates to an improvement in valves designed particularly for use as tapping valves wherein the valve is arranged to control the flow of fluid under pressure from a receptacle.

The main object of the present invention is the provision of a valve in which the parts are constructed for connection with and disposition wholly within the receptacle, with the operating member or plug of the valve held to its seat by the pressure of the fluid within the receptacle whereby such pressure aids in maintaining the valve fluid-tight in continued use.

The invention in its preferred form of details will be described in the following specification, reference being had particularly to the accompanying drawings, in which:

Figure 1 is a broken view in elevation illustrating the application of the preferred form of valve. Fig. 2 is a vertical central section of the preferred form of valve. Fig. 3 is a longitudinal section of the same. Fig. 4 is a front view. Fig. 5 is a perspective view of the plug removed. Fig. 6 is a broken view in elevation illustrating a modified form of valve in position in the receptacle. Fig. 7 is an enlarged elevation of the valve detached. Fig. 8 is a longitudinal central section. Fig. 9 is a transverse section. Fig. 10 is a front view. Fig. 11 is a view in elevation partly broken out of one type of discharge pipe for use in connection with the valve.

Referring particularly to the form of valve illustrated in Figs. 1 to 5 inclusive it will be noted that the improvement comprises a casing 1 of appropriate length comprising a cylindrical body 2 having a reduced exteriorly threaded extension 3 at the inner end thereof. Adjacent the outer end of the body is a somewhat increased diameter as at 4 and exteriorly threaded through such increased portion, the body beyond the threaded portion 4 being further increased in diametrical extent and of angular contour as at 5 whereby to provide an operating head for the casing.

The valve casing throughout that portion included between the operating head and the extreme inner end of the valve is formed with internal bore 6 the diameter of which gradually decreases from the extreme inner end of the valve toward the outer end thereof. The operating head 5 is formed with internal bore 7 of uniform diameter throughout which connects with the bore 6 but is of somewhat less diameter than the minimum diameter of said bore whereby to provide a shoulder 8 at the juncture of the bores 6 and 7. A plug 9 is designed to fit within the valve bore 6 comprising a truncated cone shaped body portion 10 of a size to accurately fit, both in length and diameter the bore 6 of the casing, the end of the body having a circular projection 11 at the forward end to fit within the bore 7 of the head, the juncture of the body 10 and projection 11 forming a shoulder 12 to coöperate with the shoulder 8 within the casing. At this time the inclined wall of the casing bore and the inclined surface of the plug are in intimate non-locking contact, after which the cap is secured in place and the valve is complete. A spring 19 is interposed between the cap and the adjacent end of the plug 9, said spring serving to maintain effective coöperation between the contacting surfaces of the plug and casing. As will be particularly noted from Fig. 3 the extension 13 of the plug projects wholly beyond the forward end of the operating head 5 of the casing so that when the valve is in place said extension 13 provides means, through the use of suitable tool for operating the plug to move the ports 17 of the plug and casing into or out of registry as may be desired. In this form, the valve is inserted in the receptacle by screwing the casing with the contained plug into an opening 20 in the receptacle, the opening being interiorly threaded to coöperate with the threaded portion 4 of the casing, and the valve as an entirety being secured in place by manipulating the same by a suitable tool coöoperating with the head 5. Any desired form of delivery spout may be used in connection with the valve described, said spout being preferably exteriorly threaded at its inner terminal to engage the portion 15 of the plug.

In Figs. 6 to 10 I have illustrated a slightly modified form of valve which includes a casing 21 having a reduced threaded extension 22 at the inner end, a reduced tu-

bular extension 23 at the forward end and an annular flange 24 arranged at the juncture of the body portion and head 23. The body portion of the valve is formed throughout its length with a central bore 25 of uniform diameter from the inner end toward the outer end, the extension 23 being formed for a portion of its length with a cylindrical opening 26 having a diameter approximately equal to the diameter of the bore, said extension being further formed adjacent its juncture with the bore 25 with an annular inwardly projecting rib 27 the inner surface of which is at the outer terminal of the bore to provide a shoulder 28.

A plug 29 is designed to be seated in the body 21 having its surface of form to snugly fit in the bore 25 of the plug. The plug is formed with a circular extension 30 having a maximum diameter corresponding to the interior diameter of the rib 27, so that when the bore is in place the shoulder 31 formed between the conical section of the plug and the cylindrical extension 30 bears against the shoulder 28 and the casing. A cap 32 is arranged to engage the threaded end or extension 22 of the casing whereby the inner end of the casing is sealed after the plug has been secured therein. The plug is interiorly formed with a conical bore 33 which extends throughout the length of the plug member having its maximum diameter at the inner end thereof, the conical bore communicating with the cylindrical bore or opening 34 in the extension 30, said cylindrical opening having a diameter corresponding to the minimum diameter of the bore of the plug. The plug and casing provided with diametrical opposing ports 35 designed to draw into registry to open the valve, that is to establish communication between the interior of the receptacle with which the valve is connected to the bore 33 of the plug.

As the exterior diameter of the extension 30 is less than the interior diameter of the opening 26 in the casing extension 23 there is provided between the said extensions in advance of the rib 27 an annular space or channel 36, and this space or channel is designed to receive the inner end of the delivery spout 37 for coöperation with this particular form of valve. The spout which may be of any desired form aside from the details described is provided with an operating handle 38 and is formed interiorly of its inner or valve engaging end with diametrically opposed pins 39. The wall of the extension 30 of the plug is formed with diametrically opposed longitudinally extending slots 40 in which the pins 39 are slidably engaged whereby the spout is so connected to the valve as to always form a medium for passage of the fluid which passes through the valve but also as means

for turning the plug for registry or non-registry of the ports 35 as may be desired, it being obvious that the engagement of the pins 39 with the slots 40 lock the spout and valve plug together against other than independent longitudinal movement of the spout. The modified form of valve is secured in the receptacle by causing the flange 34 to abut the inner surface of the receptacle to which surface it is secured by bolts or rivets, the extension 23 of the valve passing through the opening in the receptacle with the outer edge of the extension flush with the outer surface of the receptacle. In this form there is, therefore, no projection beyond the wall of the receptacle and the valve may be entirely concealed and the contents of the receptacle prevented from being tampered with by securing any desired form of seal over the end of the valve.

In both forms of valves described it is to be particularly noted the interior of the plug is of conical formation and that the exterior of the plug and the interior of the casing bore are of conical formation. Furthermore the inclinations given to various conical surfaces are toward the outer or discharge end of the valve, that is their maximum diameters are at the inner ends of the valve. This is particularly important as thereby I am enabled to use pressure of the fluid within the receptacle as a means for maintaining the valve plug in fluid sealing relation to the casing, as the pressure of such fluid will by virtue of its conical surface described tend to more tightly seat the plug in the casing.

What is claimed is:—

A receptacle tapping valve comprising a casing adapted to be secured to the receptacle and having a portion thereof projecting beyond the outer surface of the wall of the receptacle to permit of the manipulation of the casing, said casing being formed with an internal bore tapering from the inner end of the casing to a point approximately in line with the outer surface of the receptacle when the casing is in place, the bore of the casing being of true cylindrical form from the forward end of the taper to the forward end of the casing, the cylinder section of the bore being of less diameter than the minimum similar dimension of the tapered section of the bore to provide a shoulder at the juncture of such bore sections, a plug having an external surface corresponding exactly to the internal surface of and fitting both sections of the bore of the casing, the inner end of the plug approximately aligning with the inner end of the casing, the outer end of the plug extending in advance of the outer end of the casing and being formed to permit manipulation of the plug independently of the casing, the

plug and casing being each formed with diametrically opposed ports adapted to be placed in registry or non-registry to control the flow of the liquid from the receptacle, 5 and a cap having threaded connection with the inner end of the casing and limited in its application by such inner end of the casing, said cap being spaced from the inner

end of the plug, and a spring interposed between said cap and plug. 10

In testimony whereof I affix my signature in presence of two witnesses.

EDWARD P. POOLE.
